APPARATUS FOR PACKAGING PRODUCTS

Edward A. Muller, Long Island City, N. Y.

Application June 6, 1938, Serial No. 212,197

2 Claims. (Cl. 93—2)

This invention relates generally to improvements in processes of packing and more especially to improvements in apparatus for facilitating wrapping packages in sheet material, such as 5 "Cellophane" and the like.

It is presently customary to market many different types of products in packages wrapped in thin, essentially transparent sheet material, such as "Cellophane" or the like. It has been usual 10 to wrap these products by hand, that is to say, the product was enveloped in a sheet of material of appropriate size and the end of the sheet gathered together with appropriate means for holding the same in sealed condition. This procedure has been unsatisfactory for several reasons, notably it has been difficult to provide suitable sealing means for the end parts of the "Cellophane" which would present a neat and agreeable appearance. A further disadvantage is 15 that the process being composed essentially of hand operations performed in sequence does not tend to make for uniformity of product. A still further disadvantage of the prior art process referred to is that it was often difficult especially 20 with objects of irregular shape to properly envelop the object in sheet material preparatory to sealing the edges of said sheet.

It is among the more important objects of the present invention to provide new and improved 25 means for wrapping packages particularly irregularly shaped objects or packages in sheet material, such as "Cellophane" or the like whereby an essentially continuous covering of pleasant and attractive appearance is provided.

Another object of the instant invention is to 30 provide means for facilitating wrapping of objects in an essentially continuous fibrous sheet wherein means are included for uniting end and edge portions of said sheet to present an attractive and permanent seal.

A further object of the present invention is to 35 provide means for facilitating enveloping of an object especially an irregularly shaped object in a sheet of fibrous material whereby end and edge portions of said sheet are gathered together in a manner facilitating sealing thereof.

An important advantage of the package wrapping means according to the present invention 40 is that it can be adapted to use with automatic machinery or if preferred, can be used in conjunction with hand wrapping processes whereby in the latter instance, the product is of a uniformity not hitherto attained.

One of the more important features of the 45 novel package wrapping device according to the

present invention is that it comprises relatively few parts, each of which is characterized by simplicity and ruggedness of construction thereby minimizing initial cost of manufacture and rendering unlikely damage other than wear resulting from ordinary use. 5

Other objects, advantages and features of the device according to the present invention will be apparent to those skilled in the art during the 10 course of the following description.

Regarded in certain of its broader aspects, the present invention comprises a device having an opening formed therein adapted to receive a package therein, the size of said opening being arranged whereby relatively small clearance is 15 provided between the walls and the package, and one or more annular shaped members adapted to cooperate with said device for facilitating gathering together of end portions of sheet material, positioned circumjacent said package, whereby 20 said end portions of said sheet material are arranged with respect to each other in a manner facilitating sealing thereof and closure of the wrapper. 25

In order to facilitate a fuller and more complete understanding of the present invention, a specific embodiment thereof will be hereinafter described, it being clearly understood, however, that the illustrated embodiment is given solely by way of example and is non-limitative upon the 30 scope of the present invention except as expressed in the subjoined claims.

Referring then to the drawings:

Figure 1 is substantially a side elevational view 35 of a package provided with sealed wrapping according to the present invention.

Figure 2 is substantially a top plan view of the device according to the present invention used in facilitating wrapping of the package illustrated in Figure 1. 40

Figure 3 is essentially a vertical sectional view of Figure 2 taken along the line 3—3.

Figure 4 is substantially a side elevational view 45 illustrating another type of package wrapped by means including the device according to the present invention.

Figure 5 is substantially a top plan view of the device according to the present invention used in wrapping the package illustrated in Figure 4, and

Figure 6 is essentially a vertical sectional view 50 of Figure 5 taken along the line 6—6.

Referring now especially to Figures 1 to 3 inclusive, it will be noted that the wrapped package generally designated by the numeral 10, comprises an essentially flat, substantially circular 55

top portion generally designated by the numeral 11 and an essentially spherical base portion generally designated by the numeral 12.

In wrapping the package, the sheet material is placed over the top 11 and the sides and edges of said sheet are gathered together and sealed near the center point of the base 12, as will be hereinafter described.

The device according to the present invention is best illustrated in Figures 2 and 3 and comprises an essentially flat base 10 and a substantially hollow, essentially cylindrical guide member 15 positioned on said base. The interior of the guide 15 is provided with an opening 16 larger but only slightly larger than the package 10, at the place of its greatest diameter whereby sheet wrapping material 17, positioned circumjacent said largest part of said package is snugly pressed against the package by the portions of the guide member 15, defining the opening 16. The upper portion of the guide member 15 is of relatively greater interior diameter and defines an opening 18 and ledge 19, adapted to receive an essentially annular member 20 which rests upon said ledge 19, substantially as shown in Figure 3. One surface 21 of the annular member 20, is curved to conform with curved side portions of the package 10 whereby the wrapping material 17 positioned circumjacent said package is pressed thereagainst.

A second annular member 23 lesser in diameter than the interior of the annular member 20 hereinabove described, is provided and serves to gather together side and edge portions of the wrapping material 17 as will be hereinafter described.

In use, a crinkled edged cup-like shape is formed of the sheet wrapping material and the object positioned therein with the edges of the cup extending upwardly and the top of the package resting on the bottom of the cup. The object with the wrapper positioned circumjacent thereto is then positioned within the cup 15 and the annular shaped guide member 20 is then placed within the cup 15 and against the package whereby the edge and end portions of the wrapping material are moved toward the axis of the annular member 20. The ring or annular member 23 is then positioned upon the end and edge portions of the wrapping material, whereby said end and edge portions are moved into adjacency with respect to each other and disposed in essentially a common plane, thereby facilitating application of a seal 24 thereto for holding said edge and end portions in relatively fixed position. After proper adhesion between seal and wrapping is attained, the annular members 23 and 20 are removed and the package disengaged from the guide 15.

Referring now especially to Figure 4, 5 and 6, it will be noted that a package generally designated by the numeral 46 possessing an essentially frusto-conical base portion 41, cylindrical intermediate portion 42 and substantially flat top portion 43 is provided with wrapping 44 having edge and end portions joined by a closure seal 45 substantially as shown in Figure 4.

Referring now especially to Figures 5 and 6, it will be noted that a base 50 carrying supporting members 51 and 52 serves as mounting for plate 53, having an essentially circular opening 54 formed therein, said plate 53 being arranged in spaced parallelism relative to said base 50. The package being wrapped 46, as positioned in a crinkled edge cup 44 formed of the sheet wrap-

ping material and is positioned within the opening 54 of the plate 53, whereby the edges of said opening snugly press said wrapping material against the side portions of the package or object 40. It will be understood of course, that the crinkled edge portions of the wrapping material extend upwardly from the plate 53. A ring 55 is then positioned on and pressed against the end and edge portions 56 of the cup 44, whereby said end and edge portions are moved into adjacency relative to each other and are disposed in substantially a common plane whereby sealing of said end and edge portions with a closure 45 is facilitated.

After adhesion is secured between closure 45 and edge portions 56 of the wrapper 44, the annular member 55 is removed and the wrapped package taken from within the opening 54 of the plate 53.

It will be noted referring to Figures 3 and 6 particularly that during operation of the novel package wrapping and sealing means according to the present invention, that the crinkled edge portions of the package wrapper are moved into adjacency with respect to each other and disposed in a common plane by axial movement of the annular members 23 and 55 respectively, whereby sealing and closure of said end and edge portions of said wrapping material is at least largely facilitated.

It is to be understood that this improvement is capable of extended application and is not confined to the exact showing of the drawings nor to the precise construction described and, therefore, such changes and modifications may be made therein as do not affect the spirit of the invention nor exceed the scope thereof as expressed in the appended claims.

What is claimed as new is:

1. A device of the type described for facilitating closing and sealing of a crinkled edge package wrapper comprising a guide block having an opening formed therein adapted to receive said package with said wrapper loosely positioned circumjacent thereto, the interior contour of said opening substantially conforming to the outline of the package whereby the wrapper is snugly pressed against the sides of said package; a first annulus, receivable within said opening in said block and on the free extended end and edge portions of said wrapper, the contour of said first annulus adjacent said package substantially conforming to the outline of said package whereby said wrapper is pressed snugly against said package and the free end and edge portions of said wrapper are moved toward the axis of said annulus; and a second annulus, receivable within said opening in said first annulus and on the free extended end and edge portions of said wrapper, whereby axial movement of said annulus member toward said package causes said end and edge portions of said wrapper to approach each other and dispose themselves in substantially a common plane.

2. A device of the type described for facilitating closing and sealing of a crinkled edge package wrapper comprising a guide block having an opening formed therein adapted to receive said package with said wrapper loosely positioned circumjacent thereto, the interior contour of said opening substantially conforming to the outline of the package whereby the wrapper is adapted to be snugly pressed against the sides of said package with the free end and crinkled edge

portions of said wrapper extending outwardly through said opening; and a ring-like member, shaped to be received within said opening in said block and on the free extended end and edge portions of said wrapper, whereby axial movement of said ring-like member toward said package

causes said end and edge portions of said wrapper to approach each other and to dispose themselves in substantially a common plane facilitating engagement of an adhesive closure therewith.

5

EDWARD A. MULLER.
